UNITED STATES PATENT OFFICE.

GORDON E. ROEDDING, OF GRAND RAPIDS, MICHIGAN, ASSIGNOR TO CHENEY TALKING MACHINE COMPANY, OF CHICAGO, ILLINOIS, A CORPORATION OF ILLINOIS.

DESIGN FOR A PHONOGRAPH CABINET.

Application filed March 2, 1923. Serial No. 5,343. Term of patent 3½ years

To all whom it may concern:

Be it known that I, GORDON E. ROEDDING, a citizen of the United States, residing at Grand Rapids, in the county of Kent and State of Michigan, have invented a new and original Ornamental Design for Phonograph Cabinets, of which the following is a specification, reference being had to the accompanying drawing, forming a part thereof.

The figure is a front elevational view of a phonograph cabinet showing my new design.

I claim:

The ornamental design for a phonograph cabinet, as shown.

GORDON E. ROEDDING.
